UNITED STATES PATENT OFFICE.

HENRY TIEDEMANN, OF NEWARK, NEW JERSEY, ASSIGNOR TO SPLITDORF ELECTRICAL COMPANY, OF NEWARK, NEW JERSEY.

GENERATOR ATTACHMENT MEANS FOR GAS ENGINES.

1,402,548.

Specification of Letters Patent.

Patented Jan. 3, 1922.

Application filed October 27, 1919. Serial No. 333,579.

To all whom it may concern:

Be it known that I, HENRY TIEDEMANN, a citizen of the United States, residing at Newark, in the county of Essex, State of New Jersey, have invented certain new and useful Improvements in Generator Attachment Means for Gas Engines, of which the following is a description, reference being had to the accompanying drawing and to the figures of reference marked thereon.

This invention relates to means for attaching generators to internal combustion engines, and as illustrated the generator is for the purpose of supplying ignition to the engine cylinders. It will be understood and agreed that any other type of generator may be used in place of the ignition type for any purpose whatsoever. The attachment means herein shown and described is particularly adapted for use in connection with a "Fordson" tractor.

It is the object of my invention to provide attachment means for an engine of this character which is very simple and inexpensive and which may be readily applied to the said tractor engine by the owner of the tractor.

Other and further objects will be apparent to one skilled in this art after a study of the drawings and annexed specification, wherein—

Figure 1 shows a partial side view of the tractor engine with the ignition generator and attachment means in place.

Figure 2 is a view of the attachment plate looking in the direction of the arrow in Figure 1 but without the ignition generator on the plate.

Figure 3 is an end view of the installation with the cover plate broken away showing the bolt holes in the end of the attachment plate.

Figure 4 is a partial top view of the cover plate.

Figure 5 is a sectional view showing the timing shaft, timing gear and driving gear for operating the generator.

Referring now to the details, wherein like numbers refer to corresponding parts in the various views, 1 illustrates the engine cylinders in front of which a radiator 2 and fan 3 are placed. 4 is a bracket having a projecting plate 5 on which a generator 6 is adapted to be fastened in any suitable manner, such as by straps 7. To the ignition

generator 6 is fastened an advance lever 41 and an impulse coupling 42 for obtaining a hot spark at slow rotative speed of the engine crank shaft. The outer end of the plate 5 is supported by a brace 8 fastened at the bottom to one of the regular engine bolts and at the top to the outer end of the plate as by bolt 9 which passes through a slot 44 whereby the bracket 4 can be adjusted as will be hereinafter referred to. The bracket 4 preferably has a web 10 extending under the plate 5 to strengthen and support it. Extending substantially at right angles to the plate 5 is an arm 11 having a bolt hole 12 to receive a bolt corresponding to an established point of attachment on the engine. The arm 11 also has an elongated hole 13 to receive another bolt corresponding to a second established point of attachment on the engine. Extending from the arm 11 is a projection 14 carrying a set screw 15 and lock nut 16, the purpose of which will be hereinafter referred to. At the junction of the plate 5 and arm 11 a bearing block 17 is provided and, as illustrated, the top part of the bearing block 17 has a cover 18 which carries cups 19 for means of lubricating the bearings. The bearing supports a stub shaft 20 which projects beyond the bearing at one end to receive a coupling 21 of any suitable design, it being understood that the other part of the coupling is connected to the generator shaft. Carried within the bearing block 17 and cover 18 on the shaft 20 is a sprocket wheel 22 (see Figure 3). The cam shaft 23 has the usual gear 24 which engages a suitable gear on the crank shaft and this gear is enclosed within the gear case cover 25.

In order to provide a driving gear from the cam shaft 23 I remove the usual nut which holds the gear 24 in position on the cam shaft 23 and provide instead a stub shaft 26 which is interiorly threaded to engage the threads 27. The outer end of the stub shaft 26 is adapted to receive a sprocket wheel 28, the same being preferably held to the stub shaft 26 by means of a key 29 and also by means of a nut 30 and washer 31. This means of attaching the sprocket wheel to the cam shaft, I consider to be one of the important features of my attachment means. A noiseless chain 32 connects the sprocket wheel 28 to the sprocket wheel 22 thereby completing the

driving means from the cam shaft to the shaft 20. After the bracket 4 has been put in position and the sprocket wheel 28 and chain 32 installed, I cover the chain and 5 sprocket wheel 28 by means of a cover plate 33, one end of which 34 is adapted to project under the inner edge 43 of the cover 18. An oil hole 35 for oiling the chain 32 is provided, this hole being normally closed 10 by a resilient member 36 held to the cover 33 in any suitable manner, such as by rivets 37. The cover 33 carries a stud 38 on which rests the end of a clamp 39, the outer end of which is held to one of the engine studs 15 by means of the hole 40. The clamp 39 is thus used to hold the outer end of the cover 33 in position against the gear case 25, thereby protecting the chain 32 and sprocket wheel 28 from dust, dirt and other 20 foreign substances.

As can be readily seen from an inspection of Figures 1, 2 and 3 the bracket is held on the engine by means of the engine bolts which normally retain the front gear 25 cover onto the engine block, passing through the bolt holes 12 and 13 and by means of the brace 8 the lower end of which is held to the flange of the engine by means of one of the bolts that secures the bottom pan 30 of the engine to the engine block. When it is desired to adjust the tension of the chain 32, the bolts passing through the holes 12 and 13 and the bolt 9 are loosened slightly and then the set screw 15, the lower 35 end of which presses against a ledge on the engine block, is adjusted thereby causing the entire bracket to tilt about the bolt passing through the hole 12 as a pivot, the slot 13 in the flange 11 and the slot 44 in the 40 brace 8 being provided so that this tilting may take place without restraint. The bolts are then drawn down thus securing the bracket in its new position.

In installations of this character a great 45 deal of difficulty is encountered in finding a place to mount the generator and for providing a suitable drive for the same, and while I have shown a preferred form of attachment means for an engine of the type 50 mentioned, I do not wish to be limited to the exact details herein shown and described, except as limited by the scope of the appended claims.

Having thus described my invention, what 55 I claim is:—

1. Means for attaching a generator to an engine consisting of; a bracket having an arm portion with points of attachment for adjustably fastening the arm to said engine and a plate portion extending substantially at right angles to said arm, a bearing block formed at the junction of said arm and plate, bearings in said block, a cover for said bearings, a shaft carried by 60 said bearings and extending outwardly from 65

said block longitudinally of said plate portion, a generator mounted on the end of said plate portion and having connecting means to said shaft, a brace fastened at one end of said engine and at the other end to 70 outer end of said plate, a gear wheel carried on said shaft between said bearings, said engine having a driving shaft carrying a driving gear thereon, means for drivingly connecting said gears and means carried by said arm for adjusting the distance between said gears.

2. Means for attaching a generator to an engine consisting of; a bracket having an arm portion with points of attachment for 80 adjustably fastening the arm to said engine and a plate portion extending substantially at right angles to said arm, a bearing block formed at the junction of said arm and plate, bearings in said block, a cover for said bearings, a shaft carried by said bearings and extending outwardly from said block longitudinally of said plate portion, a generator mounted on the end of said plate portion and having connecting means with said shaft, a brace adjustably fastened between the outer end of said plate and the engine, a gear wheel carried on said shaft between said bearings, said engine having a driving shaft, a stub shaft fastened to the 90 end of said driving shaft, a gear on said stub shaft and means for drivingly connecting both of said gears.

3. Means for attaching a generator to an engine consisting of; a bracket having an arm portion with points of attachment for 100 adjustably fastening the arm to said engine and a plate portion extending substantially at right angles to said arm, a bearing block formed at the junction of said arm and plate, 105 bearings in said block, a cover for said bearings, a shaft carried by said bearings and extending outwardly from said block longitudinally of said plate portion, a generator mounted on the end of said plate portion and 110 having connecting means with said shaft, a brace adjustably fastened between the outer end of said plate and the engine, a gear wheel carried on said shaft between said bearings, an engine shaft having an 115 operating gear thereon, a stub shaft fastened to the end of said engine shaft and serving to hold said operating gear in place, a gear carried on the stub shaft and driving means between the last mentioned gear and the first mentioned gear.

4. Means for attaching a generator to an engine consisting of; a bracket having an arm portion with points of attachment for 125 adjustably fastening the arm to said engine and a plate portion extending substantially at right angles to said arm, a bearing block formed at the junction of said arm and plate, 130 bearings in said block, a cover for said bearings, a shaft carried by said bearings and

- extending outwardly from said block longitudinally of said plate portion, a generator mounted on the end of said plate portion, and having connecting means with said 5 shaft, a brace adjustably fastened between the outer end of said plate and the engine, a gear wheel carried on said shaft between said bearings, an engine shaft having an operating gear thereon, a stub shaft fastened 10 to the end of said engine shaft and serving to hold said operating gear in place, a gear carried on the stub shaft, driving means between the first and last mentioned gears, a cover for the last mentioned gear and the 15 driving means and means carried by the bracket arm for adjusting the center distance of the first and last mentioned gears.
5. Means for attaching a generator to an engine consisting of; a bracket having an 20 arm portion with points of attachment for fastening the arm to said engine and a plate portion extending substantially at right angles to said arm, a bearing block formed at the junction of said arm and plate, bearings 25 in said block, a cover for said bearings, a shaft carried by said bearings and extending outwardly from said block longitudinally of said plate portion, a generator mounted on the end of said plate portion 30 and having connecting means with said shaft, a brace adjustably fastened between the outer end of said plate and the engine, a gear wheel carried on said shaft between
- said bearings, an engine shaft projecting through the engine casing and having an 35 operating gear thereon within the casing, a stub shaft fastened to the end of said engine shaft, a gear carried on the stub shaft, driving means connecting the first and last mentioned gears and a cover fitting 40 over the last mentioned gear and the driving means and against the engine casing, said cover being held in position at one end by the bearing cover and by an engine clamp at the other end. 45
6. Means for attaching a generator to an engine consisting of; a bracket having an arm portion with points of attachment for pivotally fastening said arm to the engine and a plate portion extending substantially 50 at right angles to said arm, a bearing block formed integrally with and at the junction of the arm and plate, a shaft carrying a gear position in said bearing block and extending outwardly therefrom longitudinally of the 55 plate, a generator carried on the end of the plate and having connecting means with said shaft, a driving gear operated by said engine, means connecting said gears and means carried on said bracket arm cooperat- 60 ing with the pivotal fastening means for adjusting the center distance between said gears.

In testimony whereof, I affix my signature.

HENRY TIEDEMANN.
